(57) **CLAIM**

The ornamental design for an article of jewelry, as shown and described.

DESCRIPTION

FIG. 1 is a front, right-side, top perspective view of the article of jewelry, showing the new design;

FIG. 2 is a front elevational view thereof;

FIG. 3 is a rear-elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is an enlargement of area 8 in FIG. 2; and,

FIG. 9 is an enlargement of area 9 in FIG. 3.

The long-short broken lines depict enlargement areas and form no part of the claimed design.

1 Claim, 7 Drawing Sheets
